UNITED STATES PATENT OFFICE

172,581

BAND TYPE CUTOFF SAW

Robert L. Crane, Glen Lake, Minn., assignor to
Continental Machines, Inc., Savage, Minn., a
corporation of Minnesota

Application February 3, 1954, Serial No. 28,815

Term of patent 14 years

(Cl. D93—3)

To all whom it may concern:

Be it known that I, Robert L. Crane, a citizen of the United States, residing at Glen Lake, in the county of Hennepin and State of Minnesota, have invented a new, original, and ornamental Design for a Band Type Cutoff Saw, of which the following is a specification, reference being had to the accompanying drawings, forming part thereof.

Figure 1 is a perspective view, showing the front, top and one end of a band type cutoff saw embodying my new design;

Figure 2 is a perspective view showing the front, top and opposite end thereof; and

Figure 3 is a perspective view looking at the rear thereof.

The dominant features of my design reside in those portions illustrated in full lines.

I claim:

The ornamental design for a band type cutoff saw, as shown and described.
